(57) **CLAIM**

We claim the ornamental design for a bowl, as shown and described.

DESCRIPTION

FIG. 1 is a top right perspective view of a bowl, showing our new design;

FIG. 2 is a top perspective view of the bowl of FIG. 1; and, FIG. 3 is a bottom left perspective view of the bowl of FIG. 1.

The broken lines depict portions of the article that form no part of the claimed design.

1 Claim, 3 Drawing Sheets
